UNITED STATES PATENT OFFICE

GEORGE B. MARKLE, JR., OF HAZLETON, PENNSYLVANIA, ASSIGNOR TO HAZLETON MANUFACTURING CO., OF HAZLETON, PENNSYLVANIA, A CORPORATION OF PENNSYLVANIA

DESIGN FOR A CASKET

Application filed May 8, 1931. Serial No. 39,758. Term of patent 14 years.

To all whom it may concern:

Be it known that I, GEORGE B. MARKLE, JR., a citizen of the United States, residing in Hazleton, in the county of Luzerne and State of Pennsylvania, have invented a new, original, and ornamental Design for Caskets, of which the following is a specification, reference being had to the accompanying drawings.

In the accompanying drawings:

I claim:

The ornamental design for a casket, as shown.

In testimony whereof, I hereunto affix my signature.

GEORGE B. MARKLE, JR.
